UNITED STATES PATENT OFFICE.

LUCIEN BAUZILE VILLEBONNET, OF NANCY, FRANCE.

ROTARY PUMP AND VENTILATOR.

SPECIFICATION forming part of Letters Patent No. 281,165, dated July 10, 1883.

Application filed December 31, 1881. (No model.) Patented in France July 4, 1881, No. 143,730, and in England October 22, 1881, No. 4,637.

To all whom it may concern:

Be it known that I, LUCIEN BAUZILE VILLEBONNET, a citizen of the Republic of France, residing at Nancy, Department of Meurthe and Moselle, in France, officer of engineering, have invented new and useful Improvements 5 in Rotary Pumps and Ventilators, (for which I have obtained a patent in France, No. 143,730, bearing date July 4, 1881, and provisional protection in Great Britain, No. 4,637, bearing date October 22, 1881,) of which the following is a specification.

The invention, which is applicable as a pump or a ventilator, comprehends a cylinder in- 15 closing two wings that operate as pistons, the one moving to draw in the fluid by creating a partial vacuum and expelling the fluid previously drawn in, while the other is practically stationary, and forming a partition between 20 the inlet and outlet passages of the pump, a differential movement being imparted to each of said wings by means of levers and links from any suitable prime motor, all as herein- 25 after more fully described, and specifically pointed out in the claims.

In the accompanying two sheets of drawings, Figure 1 is a vertical longitudinal section, Fig. 2 is an end elevation, and Fig. 3 is a vertical transverse section, of a pump constructed according to my invention, the latter figure showing in elevation the arrangement of levers and links whereby a differential rotary motion is imparted to the piston-wings. Figs. 4, 5, and 6 are detail views of the piston- 35 wings.

Like letters of reference indicate like parts in the above figures of drawings. C indicates the pump-cylinder, provided with the fluid-inlet Y and fluid-outlet Z, as shown by the drawings. The inlet and outlet passages are located upon one-third of the periphery of the cylinder, or practically so. The cylinder is mounted upon a shaft, 1, that carries two piston-wings, 2 and 3. The former of these is mounted loosely and the latter is mounted rigidly upon the shaft in any convenient manner. As shown in Fig. 1, the wing 2 is formed upon a sleeve, S, of such a length within the cylinder as to occupy one half of

the length of the shaft 1, said sleeve extending 50 outside of the cylinder a sufficient distance to connect it with the operating mechanism, as hereinafter described. The wing 3 is likewise formed on a sleeve, S', of such a length as to occupy the other half of the length of the 55 shaft within the cylinder, to which shaft said sleeve S' is keyed, as shown in said Fig. 1, or to which it is rigidly connected by means of bolts or screws, as shown by dotted lines in Fig. 4, or by means of radial arms a, as shown 60 in Fig. 6. The wing 2 may, if desired, be connected to a short sleeve, s', having radial arms a', as shown in said Fig. 6. In either construction the wings 2 and 3 extend the full length of the cylinder, one-half of each wing 65 extending over and rotating upon the bearing or carrying sleeve of the other wing, as plainly shown in Figs. 1, 4, 5, and 6.

As hereinbefore mentioned, a differential rotary movement is imparted to the wings upon 70 and with the shaft 1 by means of the following mechanism: The sleeve S of the wing 2, that is loosely mounted upon shaft 1, is rigidly connected to a short arm or crank, 6, and to the shaft 1, upon which the wing 3 is rigidly 75 mounted, is keyed a second short arm or crank, 7. The free ends of the crank-arms 6 and 7 are respectively pivoted to the inner ends of two long links, 8 and 9, the outer ends of which long links are pivoted upon the eccentric wrist- 80 pin 5^a of a wheel, W, as shown in Figs. 1 and 2. Rotary motion is imparted to said links and crank-arms through the wheel W from an auxiliary short shaft, 4, which latter is mounted in independent bearings not in the same plane 85 as shaft 1—that is to say, shaft 4 has its axis of rotation eccentric to that of shaft 1, to which motion may be imparted from any suitable prime motor, or by hand through the medium of a crank, B. Instead of the wheel W, the 90 rods 8 and 9 may be pivoted to a crank-rod, 5, secured to shaft 4, as will be readily understood.

The operation of the rotary pump is as follows, referring more particularly to Fig. 3: Motion being imparted to shaft 4 in the direction of the arrows x x, the crank-rod 5 or the wheel W will impart a like motion to the links 8 and 9. These links in their turn com- 95

municate motion to the short arms 6 and 7, and the latter to sleeve S and its wing 2 and the shaft 1 and its wing 3, respectively. The driving-shaft 4 rotating in a plane eccentric 5 to the plane of rotation of the driven shaft and its sleeve S, it will be readily understood that the speed of the shaft or the sleeve becomes much slower as the outer ends of the arms 6 or 7 pass through that portion of the 10 circle (in which said outer ends rotate) nearest to the driving-shaft, while the speed of the shaft or the sleeve is materially increased while the outer end of their driving-crank passes through that portion of the arc farthest from 15 said driving-shaft. The shaft 1 and sleeve S are therefore rotated at a differential speed, one rotating slowly, while the other rotates rapidly. The relative speed is such or approximately such that one wing will travel 20 over two-thirds of the circumference of the casing while the other is traveling over one-third thereof. In this manner the wing 2 is made to form a partition between the inlet and outlet passages Y and Z, while the wing 3 carries the fluid in front of it to the outlet-passage, and by creating a partial vacuum behind 25 it draws fresh fluid through the inlet-passage. This position of the wings is reversed at each half-revolution of the shaft 4—that is to say, 30 when the wrist-pin 5^a has made one-half of a revolution and reached the point 14, or thereabout, the position of the links and wings will be reversed, and the wing 2 will move rapidly, while the wing 3 will move slowly.

In practice I preferably employ what I term 35 a "maintaining-wheel," W'. (Shown in Fig. 1.) Said wheel is mounted upon a hub, h, formed upon one of the cylinder-heads, and is connected to the wheel W by the wrist-pin 5^a and by means of bolts. The object of employing a second wheel, W', is to obtain a greater 40 uniformity of motion of the links and arms, and consequently of the driven shaft and sleeve S and their piston-wings, said wheel acting as or performing the function of a fly-wheel. 45

Having now fully described my invention, what I claim is—

1. The combination, with the cylinder-shaft 1, of the wing 2, loosely mounted thereon, and the wing 3, rigidly connected therewith, of 50 the arms 6 and 7 and links 8 and 9, connected together as described, and means to rotate the same, substantially as and for the purpose specified.

2. The combination, with the shaft 1, wing 55 2, arms 6 and 7, links 8 and 9, and the wheel W, of the maintaining or fly wheel W', substantially as and for the purpose specified.

In testimony that I claim the foregoing I have hereunto set my hand this 24th day of 60 September, 1881.

LUCIEN BAUZILE VILLEBONNET.
